HEBRON B. LAYMAN, OF NEW YORK, N. Y.

INTERNAL-COMBUSTION ENGINE.

1,144,424.

Specification of Letters Patent. Patented June 29, 1915.

Application filed September 9, 1914. Serial No. 860,845.

To all whom it may concern:

Be it known that I, HEBRON B. LAYMAN, a citizen of the United States, and residing at New York, in the county of New York and State of New York, have invented certain new and useful Improvements in Internal-Combustion Engines, of which the following is a specification, such as will enable those skilled in the art to which it appertains to make and use the same.

This invention relates to explosion or internal combustion engines, and particularly to engines of this class, of the sleeve valve type, and the object thereof is to improve the construction and method of assembling the separate parts of an engine of this class so as to facilitate the machining or finishing of the valve casing and reduce the cost of such work; and with this and other objects in view the invention consists in the improvements in engines of this class hereinafter described and claimed.

The invention is fully disclosed in the following specification, of which the accompanying drawing forms a part, in which the separate parts of my improvement are designated by suitable reference characters in each of the views, and in which:—

Figure 1 is a central vertical transverse section through one unit of an internal combustion engine involving a plurality of units and made according to my invention; Fig. 2 a view similar to Fig. 1, but showing only one-half of the unit, and showing a modification, and Fig. 3 a view similar to Fig. 2, but showing another modification.

In the practice of my invention, as shown in Fig. 1, the cylinder *a*, and its outer casing or jacket *a*², are formed integrally and connected at the top by a horizontal plate member *a*³, in which are formed ports or passages *a*⁴ and *a*⁵.

The explosion head *b* of the cylinder *a* is formed separately and contain an annular valve casing *b*¹, and inlet and exhaust manifolds *b*³ and *b*⁴, and the explosion chamber *b*⁵. The cylinder *a* has a reduced neck *a*⁶, which communicates with the explosion chamber *b*⁵, and the walls *b*⁶ of the explosion chamber *b*⁵ are cylindrical in form in horizontal section, and said explosion chamber is of much less dimensions transversely, than the cylinder *a*. The inlet and exhaust manifolds *b*³ and *b*⁴ are placed in communication

with the explosion chamber *b*⁵ by radial ports or passages *b*⁷ and *b*⁸, and these ports or passages are controlled by the sleeve valve *c* mounted in the valve casing *b*¹, or in an annular chamber *b*⁹, formed therein. The valve chamber *b*⁹ opens downwardly through the explosion head *b*, and said valve chamber is comparatively large in transverse section and provided with inner and outer linings *c*² and *c*³, between which the valve *c* is movable in the usual manner. By this method of forming explosion head *b* the forming and finishing of said head, or the separate parts thereof, is facilitated, and the valve chamber, the walls of which are cast integrally with the explosion head, may be machined or finished at a much less expense than is ordinarily necessary in engines of this class, it being understood that the linings *c*² and *c*³ of the valve chamber, and between which the valve is movable, may be machined or finished much more easily and expeditiously than the inner walls of the valve chamber *b*⁹.

The valve chamber *b*⁹, in this form of construction, is entirely inclosed both inside and outside thereof, by water chambers or passages *d* and *d*², and the outer chamber or passage *d*² incloses the inlet and exhaust manifolds *b*³ and *b*⁴, and said water chambers or passages *d* and *d*² are provided in the bottom thereof with ports *d*⁴ and *d*⁵, which register with the ports *a*⁴ and *a*⁵, and in this way the water chambers or passages *d* and *d*² in the explosion head *b* are placed in communication with the main water chamber or passage *a*⁷ around the cylinder *a*.

The cylinder *a* contains the usual piston *e*, and when the engine is in use, water from the radiator enters the chamber or passage *a*⁷ at or near the bottom thereof in the usual manner, and passes upwardly therethrough and into the water chambers or passages *d* and *d*², from which it passes back to the radiator in the usual manner, and in this way there is a continuous circulation of water around the cylinder *a* through the explosion head *b*, around the inlet and exhaust manifold *b*³ and *b*⁴, and upwardly on both the inner and outer sides of the valve casing *b*¹.

In the top of the explosion head *b* is a counter-sunk chamber or recess *f*, between the bottom of which and the explosion cham-

ber b^5 , or the walls thereof, is an annular space f^2 in communication with the water chamber or passage d and d^2 , and the counter-sunk chamber or recess f is placed in communication with the explosion chamber b^5 by a threaded bore f^2 into which, in practice, the spark plug is screwed.

The construction shown in Fig. 2 is exactly the same as that shown in Fig. 1, except that 10 the explosion chamber b^5 is larger, and is not inclosed by a water chamber or passage, the water chamber or passage d extending downwardly only to the top, or top wall b^{10} of the explosion chamber, and the side walls 15 of the explosion chamber are formed by the bottom walls of the valve casing b^2 .

In the construction shown in Fig. 3, the outer walls of the valve casing b and the inlet and exhaust manifolds have no water 20 jacket, but the inner water chamber or passage d is employed the same as in Fig. 1, and this water chamber or passage is placed in communication with the water chamber or passage a^4 , which incloses the cylinder a by 25 means of the ports or passages a^4 and d^4 , as in Fig. 1.

From the foregoing description, it will be seen that the main features of my improvement, and which characterizes all of the 30 forms shown, consist in forming the valve chamber entirely in the detachable head b of the engine, and from the fact that the valve chamber opens downwardly through said head, and by detaching the head b , all the 35 parts thereof, including the valve and valve chamber may be readily cleaned, or repaired, whenever necessary, and a new valve and new lining for the valve chamber may also be substituted for the old one at any time.

40 In the accompanying drawing no means for operating the valve are shown, but it will be understood that any preferred construction or mechanism for this purpose may be employed.

45 Having fully described my invention, what I claim, and desired to secure by Letters Patent is:—

1. In an explosion engine, a cylinder provided with a water jacket, and a detachable 50 explosion head mounted on said cylinder and jacket, and provided with a water chamber or chambers in communication with the water chamber between the jacket and the cylinder, said explosion head being also provided with an annular valve casing formed 55 entirely in said head and in which is mounted a sleeve valve which controls the inlet and exhaust ports or passages.

2. In an explosion engine, a cylinder provided with a water jacket, and a detachable 60 explosion head mounted on said cylinder and jacket, and provided with a water chamber or chambers in communication with the water chamber between the jacket and the cylinder, said explosion head being also pro-

vided with an annular valve casing formed entirely in said head and which opens downwardly and in which is mounted a sleeve valve which controls the inlet and exhaust ports or passages.

3. An explosion engine, provided with a detachable head having an annular valve casing formed entirely in said head and in which is mounted a sleeve valve which controls the inlet and exhaust ports or passages, 70 said explosion head being provided inwardly of the valve casing with a water chamber or passage in communication with the water chamber which incloses the cylinder.

4. In an explosion engine, a cylinder provided with a water jacket, and a detachable head, in which is an annular valve casing formed entirely in said head and a sleeve valve mounted in said casing and controlling the inlet and exhaust ports, said explosion 85 head being also provided both on the inside and outside of the valve casing with water chambers, or passages.

5. An explosion engine, provided with a detachable head containing the explosion 90 chamber and an annular valve casing, formed entirely in said head, and provided with a sleeve valve, which controls the inlet and exhaust ports.

6. A combustion engine having a cylinder 95 and a detachable head containing the explosion chamber, and an annular sleeve valve casing formed entirely in said head.

7. A combustion engine having a cylinder 100 and a detachable head containing the explosion chamber, and an annular sleeve valve casing formed entirely in said head, and opening downwardly through the bottom thereof.

8. In an explosion engine, a cylinder provided with a water jacket which is connected therewith at the top thereof, and a detachable explosion head mounted thereon and within which is an explosion chamber around which is an annular valve casing 110 formed entirely in said head and which opens downwardly through said head and in which is a sleeve valve which controls the inlet and exhaust ports.

9. In an explosion engine, a cylinder provided with a water jacket which is connected therewith above the working part of the cylinder, and a detachable explosion head mounted on said plate and within which is an explosion chamber around which is an annular valve casing formed entirely 120 in said head and which opens downwardly through said head, said head being also provided with an outer casing which incloses the inlet and exhaust manifolds and with 125 water chambers or passages both inside and outside of said valve casing and in communication with a main water chamber or passage between the cylinder and its water jacket.

10. A combustion engine having a cylinder and a detachable head containing the explosion chamber, and an annular sleeve valve casing formed entirely in said head and opening downwardly through the bottom thereof, said head being provided with supplemental water circulating passages which communicate with a main water circulating passage around the cylinder.
- 10 11. A combustion engine having a cylinder and a detachable head containing the explosion chamber and an annular sleeve valve casing formed entirely in said head and opening downwardly through the bottom thereof, said cylinder being provided with a main outer casing or jacket forming a main water chamber or passage which encloses said cylinder and said head being provided with a supplemental water chamber
- 5 or passage in communication with the main 20 water chamber or passage.
12. A combustion engine having a cylinder and a detachable head containing the explosion chamber, and an annular sleeve valve casing formed entirely in said head 25 and opening downwardly through the bottom thereof, said head being also provided both inside and outside of said sleeve valve casing with water chambers or passages.
- In testimony that I claim the foregoing as 30 my invention I have signed my name in presence of the subscribing witnesses this 4th day of September 1914.
